UNITED STATES PATENT OFFICE.

JOHN R. DOOLEY, OF CHICAGO, ILLINOIS, ASSIGNOR TO INTERNATIONAL SIGNAL COMPANY, OF CHICAGO, ILLINOIS, A CORPORATION OF ILLINOIS.

DESIGN FOR A SIGNAL-LAMP.

49,473.

Specification for Design.

Patented Aug. 1, 1916.

Application filed April 22, 1914. Serial No. 833,812. Term of patent 3½ years.

To all whom it may concern:

Be it known that I, JOHN R. DOOLEY, a citizen of the United States, residing at Chicago, in the county of Cook and State of Illinois, have invented a new, original, and ornamental Design for Signal-Lamps, of which the following is a specification, reference being had to the accompanying drawing, forming part thereof.

The figure is a perspective view of a signal lamp showing my new design.

I claim:

The ornamental design for a signal lamp as shown.

JOHN R. DOOLEY.

Witnesses:

LEWIS T. GREIST,
MAURICE DARMSTADTER.
